[57] CLAIM

The ornamental design for a combined eye wear and flexible strap temples, as shown and described.

DESCRIPTION

FIG. 1 is a perspective view of a combined eye wear and flexible and flexible strap temples showing my new design; FIG. 2 is a front elevational view thereof; FIG. 3 is a rear elevational view thereof; FIG. 4 is a left side elevational view thereof, wherein the right side elevational view is a mirror image thereof; FIG. 5 is a top plan view thereof; FIG. 6 is a bottom plan view thereof, wherein the portion shown in phantom FIGS. 1-5 is omitted for clarity; and, FIG. 7 is a perspective view showing thereof in an operable environment.

The broken line showing of the pendants and the wearer's head is for illustrative purposes only and forms no part of the claimed design.
